UNITED STATES PATENT OFFICE.

CARL SCHWARZ, OF CHARLOTTENBURG, NEAR BERLIN, GERMANY, ASSIGNOR TO WESTINGHOUSE ELECTRIC & MANUFACTURING COMPANY, A CORPORATION OF PENNSYLVANIA.

SYSTEM OF RADIO COMMUNICATION OVER WIRES.

Application filed October 31, 1921, Serial No. 511,835, and in Germany May 26, 1921.

This invention relates to radio signaling. It is particularly applicable to signaling over line wires where the line consists of three or more wires. The invention is an improvement over the system shown in my application, Ser. No. 511,831, filed Oct. 31, 1921, Patent 1,622,679, March 29, 1927.

It is an object of this invention to provide a means whereby any one of a number of 10 stations distributed along a line may be called by any of these stations.

It is a further object of this invention to provide a means whereby the connections at the calling and the called stations may be 15 rearranged so that communication between these stations can be carried on without interference from the other stations in the system and without interfering with said other stations.

20 It is a further object of this invention to provide a method by which signaling along wires between a plurality of stations may be done without requiring as many different signaling frequencies as have heretofore been 25 necessary.

Other objects of the invention and details 30 of the construction used will be apparent from the following description and the drawings, in which

Figure 1 is a diagrammatic showing in 35 detail of the connections at one station, the connections in the other figures being shown in less detail.

Fig. 2 is a diagrammatic showing of the 40 connections at two stations.

Fig. 3 is a similar showing of a different 45 arrangement of such connections.

Fig. 4 is a diagram showing connections 50 for three stations.

Fig. 5 is a diagram illustrating the connection 55 which results from changing the switches in Fig. 4.

The connections shown in Fig. 1 have been 60 described in considerable detail in the above 65 identified application and they are, therefore, only briefly described here. The line wires 15, 16 and 17 have associated with them three antennæ 1, 2 and 3. The inductors 4, 5 and 6 are connected to the several antennæ and 70 to the common point 14 which is connected to the ground. Condensers 7, 8 and 9 in 75 shunt to the several inductors, respectively, afford means for tuning each of the three

antenna circuits. A sending device indicated by the coils 10 and 11 is coupled with 55 the circuits of antennæ 1 and 2. A receiving device 12 is coupled with the remaining antenna circuit. In the operation of this apparatus, the coils 4 and 5 are so balanced 60 that the energy delivered from the coils 10 and 11 does not affect the receiving apparatus connected to the coil 12.

In Figure 2, the connections and the several 65 line wires are indicated by condensers 18, 19 and 20 instead of by antennæ as shown in Fig. 1, although both methods of coupling are equally available. At station A, the two 70 coils 4 and 5 are energized by the coils 10 and 11 associated with the sending device S₁. At station B, the similarly numbered coils are 75 energized by the sending device S₂. The coils 4 and 5 at S₁ together with the condensers 18 and 19 may be regarded as constituting two arms of a Wheatstone bridge. The other two arms are made of the coils 4 and 5 and the condensers 18 and 19 at station B. The line wires 15 and 16 constitute 80 two junctions of the Wheatstone bridge, the other two junctions being the points 14. The coils 6 and condensers 20 together with the line wire 17 thus constitute a diagonal connection of the Wheatstone bridge and, if the 85 balancing were perfect, no energy would be imparted to the receiving devices E₁ and E₂. As explained in connection with the above identified case, the balancing may be made sufficiently perfect to prevent the sending 90 device S₁ from influencing the receiving device E₁, but it will influence, at least slightly, the receiving device E₂. This is because of the necessary difference between the two line 95 wires 15 and 16. If desired, this difference may be increased by artificially increasing the lack of balance, for example, by adding an extra connection to one of the wires.

When the connections are as shown in Fig. 3, the sending device S₁ delivers practically all of its energy to the receiving device E₂ and the sending device S₂ is similarly related to the receiving device E₁. Signals 100 received at station B from station A are thus much stronger and clearer with the arrangement shown in Fig. 3, even though some signaling is possible with the arrangement shown in Fig. 2.

105 This principle is used for connecting a

number of stations, as shown in Fig. 4.. The switches indicated in this figure are so set that the stations are all connected in the same way so that they are related like the two stations shown in Fig. 2. Sufficient unbalancing will be provided to enable the sending device at any station to call any other station. This may be done, for example, by sending out a code signal. The called station will then change its connections. For example, it may interchange the coil 6 and its condenser with either other branch of the star connection. This will result in placing the called and calling station in the relation shown in Fig. 3. For example, if station I has called station II and as a consequence station II has altered its connections, stations I and II will then be related in the way illustrated in Fig. 3, while stations I and III will still be related in the way illustrated in Fig. 2. It will, however, be noted that, after this change, stations II and III are related as illustrated in Fig. 3 so that the called station is in communication with other stations beside the calling station.

This difficulty is reduced by using the system shown in Fig. 5. Here the several stations are differently connected. With the connections as illustrated, station I can at any time call either station II or station III. No preliminary unbalancing is needed. If station I desires to communicate with station III without being heard at station II, the coil 6 and its condenser at station I may be interchanged with coil 4 and its condenser. This will result in permitting station I to send signals to station III which will not be heard in station II, but station III when replying will be sending signals that station II can hear. For this reason, only part of the conversation could be heard in station II and the conversation could be

so managed that it would not be intelligible there, if this is desired.

It will be obvious that the system described can be applied to more than three stations, for example, by using more than three line wires. It is equally obvious that over three line wires the system can be applied to a larger number of stations by using different frequencies for signaling between different groups of stations. Numerous other changes will occur to those skilled in the art. I, therefore, do not wish to limit the invention except as necessitated by the prior art or indicated by the claims

I claim as my invention:

1. In a radio signaling system, a plurality of line wires, a plurality of stations along the line, a sending device at each of said stations directly coupled to two of the wires, a receiving device at each of the stations directly coupled to another wire, and means at each station for interchanging the devices whereby the receiving device will be directly coupled to one of the wires to which the sending device was directly coupled.

2. In a radio signaling system, a line comprising a plurality of wires, a plurality of stations along the line, a sending device, and a receiving device at each station, the sending device being directly coupled to all but one of the wires and the receiving device being directly coupled to the remaining wire, the wire to which the receiving device is directly coupled being different at different stations and means at each station for interchanging the coupling so that the receiving device is directly coupled to one of the wires to which the sending devices at other stations are directly coupled.

In testimony whereof I affix my signature.

CARL SCHWARZ.
